UNITED STATES PATENT OFFICE.

GEORGE S. GATCHELL, OF ROSELLE PARK, NEW JERSEY, ASSIGNOR TO THE SINGER
MANUFACTURING COMPANY, A CORPORATION OF NEW JERSEY.

LOOPER-THREAD-CONTROLLING MECHANISM FOR SEWING MACHINES.

1,408,185.

Specification of Letters Patent. Patented Feb. 28, 1922.

Application filed February 6, 1919. Serial No. 275,296.

To all whom it may concern:

Be it known that I, GEORGE S. GATCHELL, a citizen of the United States, residing at Roselle Park, in the county of Union and State of New Jersey, have invented certain new and useful Improvements in Looper-Thread-Controlling Mechanisms for Sewing Machines, of which the following is a specification, reference being had therein to the accompanying drawings.

In the formation of chain-stitch seams by machines of the well known type embodying a threaded looper in cooperation with one or more reciprocating needles, as disclosed, for example, in U. S. patents to Muther et al., No. 299,569 (one needle) and No. 583,415 (two needles), and Molyneux No. 1,266,036, (four needles), it is desirable from the standpoint of good sewing that the needle-loops be fully drawn up to the under surface of the work regardless of variations in the length of stitch or character of work being sewed. In other words, it is desirable that the appearance of the looper-thread and needle-loops at the under side of the seam be uniform under varying sewing conditions.

The looper of machines of the type under consideration commonly passes a loop of looper-thread through one or more needle-loops and then presents the looper-loop for entry by the succeeding needle-loop or loops which, in turn, is or are entered by the looper carrying a new looper-loop, and so on. When the needle-loops are drawn up, the looper-thread is drawn into its usual circuitous or zigzag course through and about the needle-loops, and it will thus be clear to those skilled in the art that, other conditions being equal, a greater length of looper-thread will be required for a long stitch than for a short stitch.

In operating machines of the above type, it is customary at times to "chain off", that is, to sew when there is no work in the machine, the threads being concatenated to form a chain which is fed out from under the presser-foot by a feed-dog section in rear of the sewing point. It has been observed that for a given stitch length adjustment of the feed, less looper-thread is used per stitch when "chaining off" than when sewing with work under the presser-foot. This is probably due to the fact that the chain is

of an elastic nature and the feeding element which engages the chain in rear of the sewing point will stretch the chain thus allowing the stitches being formed to crowd more closely together on the usual stitch-supporting tongue or tongues in the throat-plate, than they would if formed in material.

Adjustment of the needle-thread tension device will have a greater or less effect upon the degree to which the needle-loops are drawn up by the needle-thread take-up mechanism and, while it is desirable to adjust the needle-thread controlling mechanism so that the needle-loops will be fully drawn up to the under surface of the work, it is a fact that if for any reason these loops are not fully drawn up, less looper-thread is required per stitch.

Thus the amount of looper-thread used per stitch depends upon the stitch length and whether the machine is sewing in material or "chaining off," as well as upon other more or less variable conditions, such as the adjustment of the thread tension and needle-thread take-up means.

It has heretofore been common to provide machines of the type referred to with looper-thread controlling mechanism comprising an intermittently acting thread-nipper, a pull-off on the supply side of the nipper and a take-up or slack-thread controller on the work or looper side of the nipper. In these machines, as the looper starts forward to enter the needle-loop or loops, the looper-thread is supposed to be free from slack and the take-up is designed to have sufficient action on the looper-thread to prevent the formation of slack as the looper advances, thereby overcoming the tendency of the looper-thread to buckle in front of the eye of the looper. As soon as the looper-beak has entered the needle-loop or loops, the nipper is opened, and as the looper advances to the end of its stroke it draws through the nipper an amount of looper-thread sufficient for the formation of the next stitch; this amount having been previously measured from the supply by the pull-off. As the looper retracts, the needles descend in the customary manner, passing down beside their previously formed loops on the looper and entering the looper-loop. After the looper has shed the needle-loop or loops and nears the end of its retracting

stroke, the needle-thread take-up mechanism draws up or tightens the needle-loop or loops which thereupon absorb or draw into the stitch the supply of slack looper-thread afforded by the looper. Thus, when the looper reaches the end of its retracting stroke, the looper-thread is free from slack.

While it is possible to sew under these conditions, the results from a practical standpoint are not fully satisfactory, inasmuch as the usual variations in sewing conditions are not taken care of. For example, when the feed is shortened, or when chaining off, less looper-thread is required per stitch, and the amount of looper-thread drawn past the nipper by the advancing looper is more than enough for the stitch being formed. As a result, there is slack in the looper-thread after the looper has reached the end of its retracting stroke and, as the looper starts forward, the take-up does not have sufficient action to absorb this slack-thread and, in addition, take care of the slack-thread normally given up by the looper during the first part of its advancing stroke. Thus, there is danger that the looper-thread will buckle in front of the eye of the looper and get on the wrong or front side of the looper point, thus causing thread-breakage or skipping of stitches.

In other words, the looper-thread controlling mechanisms of the prior art will properly control the looper-thread only under one fixed set of conditions. If, then, the feed is shortened or an attempt is made to "chain off," the machine is very apt to break thread or skip stitches. On the other hand, if the feed is lengthened, the fixed amount of slack looper-thread afforded per stitch will not permit the needle-loops to be fully drawn up and the appearance of the stitch will be unsatisfactory.

The primary object of the present invention is to provide a looper-thread controlling mechanism of a flexible or compensating character such that the appearance of the sewing will be uniformly satisfactory under the varying conditions commonly met with in practice, such thread controlling mechanism affording sufficient slack looper-thread to permit the needle-loops to be fully drawn up, and preventing the buckling of the looper-thread in front of the eye of the looper as the latter advances, accomplishing both of these results under all conditions of adjustment of the feed and regardless of whether the machine is sewing in material or "chaining off."

Further objects of the invention will appear from the following description and claims.

To the attainment of the ends in view, the stroke of the looper is preferably made sufficient to draw enough looper-thread through the nipper for maximum require-

ments, that is, when sewing the longest stitches for which the machine is adapted, and the pull-off is designed to be capable of measuring this amount of thread from the supply. The nipper, instead of being timed as heretofore to release the looper-thread only during the last part of the advancing stroke of the looper, is further timed to release the looper-thread momentarily just after the needle-loops have been drawn up, which usually occurs at the time the loopers are fully down and the looper fully retracted.

In the present instance the relation of the pull-off to the nipper is a feature of great importance; the pull-off being preferably so timed that it is pulling the looper-thread rather rapidly from the supply at the time of the momentary release of the looper-thread by the nipper. The result is that whatever slack-thread there may be between the nipper and the work, as the looper is just starting forward, will be quickly pulled back through the nipper by the pull-off before the looper has travelled a material distance. In other words, any surplus or left over looper-thread from the last stitch forming operation will be drawn back to the supply side of the nipper by the pull-off, prior to the next stitch-forming operation. Thus the looper-thread will be free from slack as the looper advances, whether or not the supply of looper-thread pulled forwardly through the nipper is fully absorbed in the last stitch.

The invention will be more particularly explained in connection with the accompanying drawings in which Fig. 1 is a left side elevation of a machine embodying the invention. Fig. 1^a is a perspective view of a structural detail of the looper-driving mechanism. Fig. 2 is a horizontal section through the standard of the machine at an elevation above the work-arm, showing the latter in plan. Fig. 3 is a plan view of the throat-plate and feed-dogs. Fig. 4 is a diagram illustrating the relative timing of the needle, looper, looper-thread take-up, looper-thread pull-off and looper-thread nipper. Figs. 5, 5^a, 5^b and 5^c illustrate the positions of the pull-off cam, nipper-cam, take-up cam and stitch-forming implements, respectively, at the period of the cycle when the needles are fully down. Figs. 6, 6^a, 6^b and 6^c are similar views at the period when the needles are rising after the advancing looper has entered the needle-loops. Figs. 7, 7^a, 7^b, and 7^c are similar views at the period of the cycle when the needles are up and the looper is at the end of its advancing stroke. Fig. 8 is a detail perspective of the supporting bracket for the take-up thread-guides and the nipper-springs and Figs. 9 and 10 are plan and longitudinal sectional views of the seam made by the machine.

While the invention is susceptible of em-

bodiment in chain-stitch machines generally, irrespective of the number of needles employed or the type of the machine frame, I have chosen for the purpose of this disclosure 5 to embody it in the four-needle, single-looper feed-up-the-arm machine disclosed in my copending application Serial No. 185, 446, filed August 10, 1917.

As more fully disclosed in said copending 10 application, the machine-frame comprises the base 1 from which rises a hollow standard 2, carrying the bracket-arm 3 terminating in the head 4 within which are mounted the usual reciprocating needle-bar 5 and 15 presser-bar 6. In the present instance, the needle-bar 5 carries four needles 7 and the presser-bar 6 carries the presser-foot 8.

Supported at its rearward end by the standard 2 is the hollow work-supporting arm 9 carrying at its forward or free end a throat-plate 10 and end-cap 11 within which is housed the threaded looper 12. The looper 12 is mounted on the forward end of the looper-shaft 13 extending within and longitudinally of the work-arm 9 and receiving oscillatory movements from an eccentric 14 on the main-shaft 15 through a pitman 16 and crank 17. Endwise sliding movements 25 are imparted to the looper-shaft by means 30 of an eccentric 18' which is embraced by the strapped end of a pitman 18 the opposite end of which is connected to the upstanding arm 19 of a rock-lever fulcrumed upon but rocking independently of the shaft 20. 35 The depending arm 21 of said rock-lever is connected by a link 22 to a ball 23 at the rear end of the looper-shaft. The eccentrics 14 and 18' on the main-shaft thus operate to impart the usual endwise reciprocatory and 40 sidewise movements to the looper.

The needles 7 and looper 12 cooperate in the usual manner common to machines of this type to form the seam illustrated in Figs. 9 and 10 wherein the abutted edges of 45 material *a*, *a'* are shown as being penetrated by the needle-loops *b* which at the under side of the work are concatenated with the looper-thread *c* in a well known manner.

The feeding mechanism may be of any 50 usual type but is preferably constructed substantially in accordance with the disclosure of my said copending application. The fulling and main feed-dogs 24 and 25, respectively, are carried at the forward ends 55 of the usual fulling and main feed-bars 26 and 27 extending within and lengthwise of the work-arm 9. Rising and falling movements are imparted to the feed-bars by means of the feed-lifting lever 28 pivoted 60 within the work-arm at 29 and actuated by means of the pitman connection 30 with an eccentric on the main-shaft 15. At its forward end 28' the feed-lifting lever 28 is adapted to slidably support the feed-bars 65 26 and 27. Endwise feeding movements are

imparted to the feed-bars by means of the adjustable link connections 31 and 32 with the slotted feed rocker-arms 33 and 34 actuated by means of the pitman connection 35 with the main-shaft. It will be noted that 70 the link 32 may be adjusted in the rocker-arm 34 by a treadle connection, while the machine is in operation; the treadle connection comprising a chain 36, lever 37, 37' pivoted at 37*, a spring 38 and link 39. The 75 main feed may be adjusted by shifting the rear end of the link 31 along the slotted feed-rocker 33, as will be readily understood.

Referring to Fig. 3 it will be seen that the main feed-dog 25 includes two sections 25^a 80 which are directly in rear of the usual stitch-supporting tongues 40 on the throat-plate 10. The feed sections 25^a operate to engage the stitched seam and feed it away from the needles. When "chaining off" the 85 feed-sections 25^a engage the chain and pull it off of the tongues 40 on which it is formed.

The machine is equipped with needle-thread take-up cams 41 which take up or tighten the needle-loops as they are shed from the looper and control slack in the needle-thread at all times during the stitch-forming cycle.

The looper-thread controlling mechanism with which the invention is more particularly concerned, is similar to that disclosed in my said copending application except that the timing of the take-up, pull-off and thread-nipping devices has been modified in certain important particulars as will be 100 hereinafter explained. Journaled within and crosswise of the work-supporting arm 9 is a shaft 42 carrying a gear 43 which meshes with a gear 44 turning upon the fixed stud-shaft 45; the gear 44 meshing with the driving gear 46 on the main-shaft 15. The gear ratios are so chosen that the shaft 42 is 105 driven at the same speed as the main-shaft.

Mounted on the shaft 42 are the pull-off and take-up cams 47 and 48, respectively, 110 and the nipper-actuating cam 49. The take-up cam comprises a pair of spaced cam-disks between which is supported the usual cast-off 50. Mounted on the bracket 56 at 51' is the thread-guiding fork 51, the tines of 115 which are apertured at 52 is provided to present the looper-thread to the action of the take-up cam. The pull-off cam 47 operates in a similar manner with the cast-off wire 55 and the thread-guiding fork 53, 120 the tines of which are apertured at 54. The nipper-operating cam 49 acts upon a pair of superposed nipper-springs 55* carried by the bracket 56 which supports the thread-guiding fork 51. 125

The looper-thread travels its usual course from one of the tension devices *t* on top of the bracket-arm, down through the tube 57, through the guiding apertures 54 of the pull-off fork 53, thence between the nipper- 130

- springs 55^x and through the apertures 52 of the take-up fork 51, thence into the thread-receiving slit 58 extending lengthwise of the work-arm, and out through the guide 59 at the front end of the work-arm. From the guide 59 the looper-thread leads to a thread-guide 59' at the heel of the looper and thence to the usual thread-eye 59^x at the point of the looper.
- 10 The timing of the present pull-off, nipper device and take-up, which, in a general sense, is of great importance will be explained in detail in connection with the preferred embodiment of the invention as illustrated in Figs. 4 to 7, inclusive. Referring to Fig. 4, and starting with the main-shaft set at 0°, the needles up and the looper forward, it will be seen that the nipper-springs 55^x are just at the point of being closed upon the looper-thread by the hump 60, Fig. 7^a, of the cam 49; at which time the needles are beginning their descent and the looper is beginning its retracting stroke. With the nipper-springs closed, the take-up 48 rapidly absorbs the slack-thread afforded by the retracting looper as the main-shaft turns from 15° to 90°. The cam 47 is preferably formed with a hump 61, Fig. 7, which operates, say, from 80° to 120° to pull some thread from the supply but not enough for the next stitch. It is desirable, though not essential, that the pull-off act at this time to permit of a reduction of the amplitude of pull-off action at a later period of the cycle, whereby abrupt or harsh cam actions on the looper-thread may be avoided. From 90° to 180° the take-up 48 gives up thread to the looper and to the contracting needle-loops which have been shed by the looper. At 180° the needles are down, the looper is at the rear end of its stroke and the needle-loops shed from the looper are fully drawn up, thereby having absorbed into the stitch a supply of looper-thread given up by the take-up.
- 45 At or slightly before the 180° point, a rapid pull-off action begins, see also Fig. 5, and continues to the 250° point, Fig. 4. At, or just after the beginning of this rapid pull-off action, and just as the looper is starting forward, but before it has travelled a material distance, the nipper-springs 55^x are permitted to open for a brief interval, from 185° to 205°, Fig. 4, so that the pull-off 47 may draw back through the nipper-springs 55^x any slack or unused looper-thread remaining on the looper side of the nipper-springs 55^x after the last stitch has been completely drawn up by the needle-thread take-up devices. This pulling back of the unused or slack looper-thread regardless of the amount thereof, prior to the seizure of the new needle-loops, permits the next stitch-forming operation to be invariably

begun under the same conditions as regards the looper-thread. In other words the looper-thread will invariably be free from slack as the looper begins its advancing stroke. This will be so regardless of the adjustment of the feed or any other of the usual variation in sewing conditions. As a result the hump 48' of the take-up cam 48 will always have sufficient action (225° to 255°, Fig. 4) to prevent the buckling of the looper-thread in front of the eye of the looper and the consequent thread breakage or skipping of stitches. If a partial supply of thread for a stitch is not pulled off while the looper is retreating it will be necessary to pull off a full stitch supply while the main-shaft turns say from 180° to 255°, Fig. 4. The pull-off curve representing this period would therefore be steeper.

After the pull-off has measured enough thread from the supply to meet the maximum requirements for a new stitch (260°, Fig. 4) the nipper-springs are again opened and the pull-off rapidly gives up looper-thread to the advancing looper, Fig. 6, which in travelling to the end of its stroke, Fig. 7^c, pulls through the nipper and take-up enough looper-thread for the longest stitch which the machine is designed to make. After the looper retracts and the needle-loops are tightened, any surplus looper-thread is pulled back through the nipper by the pull-off at the period of the cycle when the looper is substantially at the end of its retracting stroke and before it has travelled a material distance toward the needles. Although preferable, it is not necessary that the nipper be closed after the surplus looper-thread has been pulled back through the nipper by the pull-off. The pull-off could be depended upon at this time to prevent the buckling of the looper-thread in front of the eye of the looper as the looper advances to seize the needle-loops. In this event the hump 48' of the take-up which according to Fig. 4 acts upon the looper-thread from the 210° point to the 255° point could be dispensed with. While the timing is broadly important, the details thereof are susceptible of considerable variation within the scope of the invention as defined in the claims.

The invention is not to be understood, therefore, as limited to the exact construction shown and described, as the principle thereof is obviously susceptible of embodiment in various types of chain-stitch machines and in connection with various types of pull-off, take-up, and thread-nipping devices; the specific character and exact timing of such devices being unessential so long as the general relationship and timing is such that the unused looper thread is pulled back

to the supply side of the nipper, whereby the next stitch is invariably begun under the same conditions as regards the looper-thread.

Having thus set forth the nature of the 5 invention, what I claim herein is:—

1. Looper-thread controlling mechanism for sewing machines comprising, one or more needles, a looper, means for imparting advancing and retracting movements to the 10 looper, an intermittently acting thread-nipper, and means for pulling back to the supply side of the nipper any slack or unused looper-thread remaining on the work side of the nipper after the stitch has been 15 drawn up.

2. Looper-thread controlling mechanism for sewing machines comprising, one or more needles, means for drawing up the needle-loops, a looper, means for imparting 20 advancing and retracting movements to said looper, a looper-thread take-up, a pull-off, an intermittently acting thread-nipper between said take-up and pull-off, said pull-off being constructed and timed to pull back 25 through the nipper any surplus of looper-thread on the take-up side of the nipper after the stitch has been drawn up.

3. Looper-thread controlling mechanism for sewing machines comprising, one or 30 more needles, a looper, means for imparting advancing and retracting movements to said looper, a take-up, a pull-off, an intermittently acting thread-nipper between said take-up and pull-off, said nipper being timed 35 to open during the latter part of the advancing stroke of the looper to permit the looper to draw enough thread to reach the end of its advancing stroke, said nipper being further timed to open after the stitch 40 has been drawn up and during the thread-absorbing action of the pull-off, to permit the pull-off to pull back any slack remaining in the looper-thread prior to the next stitch-forming operation.

4. In a sewing machine, in combination, one or more needles, means for drawing up the needle-loops, a thread-carrying looper, a looper-thread take-up, an intermittently acting looper-thread nipper, and a looper 50 thread pull-off, the nipper being timed to permit the passage of the looper-thread after the stitch has been drawn up, and the pull-off operating to pull back any surplus looper-thread remaining on the looper side

of the nipper after the stitch has been drawn 55 up, whereby the looper-thread will be substantially free from slack at the beginning of the next stitch-forming operation, regardless of variations in sewing conditions.

5. In a sewing machine, in combination, 60 one or more needles, a thread-carrying looper, a looper-thread nipper, a take-up operating on the looper-thread between said nipper and looper, means timed to operate said nipper to hold the looper-thread during 65 the major portion of the retracting stroke of the looper and to release the looper-thread substantially during the period of reversal of the looper at the end of its retracting stroke, and means for pulling back through 70 the nipper any slack looper-thread remaining on the looper side of the nipper at the aforesaid time of release of the looper-thread.

6. In a sewing machine, in combination, 75 one or more reciprocating needles, means for drawing up the needle-loops, a thread-carrying looper having reciprocating loop-seizing and shedding movements, an intermittently acting looper-thread nipper, a looper-thread 80 take-up timed to take up the slack of the looper-thread during the first part of the retracting stroke of the looper, a pull-off for measuring looper-thread from the supply, said nipper being timed to open when the 85 stitch is drawn up and during the action of said pull-off, whereby any slack looper-thread on the work side of the nipper will be drawn back through the nipper by the pull-off prior to the seizure of the new needle-loop by the looper. 90

7. In a sewing machine, in combination, one or more needles, a looper, means for imparting advancing and retracting movements to said looper, a looper-thread take-up, a looper-thread nipper, and a looper-thread pull-off timed to pull off a partial supply of thread for the next stitch during the retracting stroke of the looper and the remainder of the supply during the advance 95 of the looper, said nipper being timed to release the thread while the pull-off is absorbing thread and prior to the seizure of needle-loops by the advancing looper. 100

In testimony whereof, I have signed my 105 name to this specification.

GEORGE S. GATCHELL.
